UNITED STATES PATENT OFFICE

CHARLES JOSEPH RHODES, OF WAKEFIELD, ENGLAND

PRESS FOR DRAWING SHEET METAL

Application filed March 26, 1931, Serial No. 525,413, and in Great Britain December 24, 1930.

This invention relates to presses for drawing sheet metal, and refers to presses of the kind in which, in order to effect deep drawing, the centre block of the lower die is caused to move upwards during the downward movement of the upper die, this movement being effected by mounting the said block upon a rod actuated by levers operably connected with the even pressure table.

In order to avoid damage to the metal or creasing due to variation of the pressure exerted by the die upon the metal during the drawing operation, a spring was provided, arranged to act upon the even pressure table in a manner such that the above objections were avoided. Provision was made whereby the resistance of the spring could be regulated. For certain practical reasons the use of a spring in cases where very deep drawing is required, is not desirable.

The present invention has for its object certain improvements whereby the use of a spring for the purpose of varying the pressure is dispensed with.

According to the present invention, weights are employed, so arranged as to adjust the resistance to the pressure exerted by the die upon the metal.

In order that the invention may be the better understood, drawings are appended in which:

Fig. 1 is a sectional fragmentary front elevation showing one form of the press having the present improvements applied thereto.

Fig. 2 is a view showing a modification.

Fig. 3 is a sectional view showing a certain detail.

Referring to Fig. 1 of the accompanying drawings, in which only such parts are shown as are necessary for the proper understanding of the invention, 1 indicates a portion of the frame of the machine at the upper end of which is provided the table indicated by 2, and upon which table is secured a body 3 upon which is mounted the lower die 4, whereby in combination with the upper die 5 carried upon a crank operated ram 6, the disc to be acted upon is cut from the sheet.

7 indicates a pressure or draw ring disposed within the die 4, and supported by pins

8 passing through perforations 9 formed in the plate 3, and supported at their lower ends upon a second table 10 disposed beneath the table 2.

The table 10 is perforated for the free passage of a tubular rod 11, which is supported at its upper end, by means of a flange 11a, within a stepped bush 11b, which in turn is similarly supported within the body 3, the said rod at its lower end passing through a bracket 12 comprising an upper member having upon its under surface and at each end a pair of downwardly extending lugs such as 13.

14 indicate nuts or collars disposed upon the lower end of the rod 11 and arranged one upon each side of the upper member of the bracket to prevent movement of the said bracket longitudinally of the rod.

Formed upon the underside and at each end of the table 10 is a pair of lugs such as 15 which are bored to form bearings for spindles 16 upon each of which is pivotally mounted the upper end of a downwardly extending bar 17.

Each of the bars 17 has upon its outer face and approximately in the centre of its length, a short rack 18, a similar rack indicated by 19 being provided upon the inner surface, extending upwards from the lower end 80 thereof.

The respective pairs of lugs 13, which as hereinbefore described are formed upon the underside of the table 10, are each bored to form bearings for a spindle 20, upon each of which spindles is mounted a pinion 21 which engages with the adjacent rack 19, the other side of each of the said pinions engaging with a rack 22 provided upon a body 23 disposed between the pinions and secured by means of nuts 23a upon the lower end of a rod 24 which freely passes upwardly through the bore of the rod 11, and is screwed at its upper end into the forming block 25.

Formed integral with the bracket 12 at each end thereof, and extending horizontally therefrom is a pair of lugs such as 26, the said lugs being so arranged that there is one upon the rear and forward sides of each bar 17. Each of the pairs of lugs 26 extend outwardly

somewhat beyond the outer faces of the bars 17, and are bored at their outer ends to form bearings for spindles 27 upon each of which is pivoted a lever 28.

5 The inner end of each of the levers 28 is provided with a toothed sector 28a which engages with the rack 18 of the respective bars 17 and the outer end of each of the said levers is provided with a weight 29 which is adjustable longitudinally thereof and may be clamped in the desired position by means of a clamping bolt 30.

The aforementioned spindles 20 are of such length that they each project outwardly somewhat beyond their bearings at each end. 15 Mounted upon the respective rear and forward ends of the spindles 20 is a horizontally disposed body 31 which extends at its ends somewhat beyond the outer side faces of the bars 17, the arrangement being such that the said rods each extend between the said bodies carried in bearings formed at the outer ends of the bodies 31 and extending therebetween at each end is a spindle 32 upon which is mounted a roller 33, which engages with the face of the adjacent bar 17 to thus maintain the rack 19 in engagement with the respective pinion 21.

Instead of arranging for the weights to be 30 adjustable, they may be fixed, as shown in Fig. 2, in which case provision is made for damping their effect.

The means for damping the effect of the weights comprises plates 33 of suitable material carried upon shoes 34 adjustably mounted by means of pins 35 upon bodies 36 mounted upon the respective spindles 32 as shown in Figs. 2 and 3, clamping bolts 37 being provided within the bodies 36 where- 40 by the shoes may be moved to bring the plates 33 into frictional contact with the bars 17.

38 indicates an ejector whereby as the die 5 moves upward the article is ejected from the said die. The operation of the machine 45 is as follows:—

As the ram 6 descends, the upper die 5 causes the draw ring 7 to be depressed, this motion being transmitted through the pins 8 to the table 10 causes the same to also descend together with the bars 17. This downward movement of the bars 17 causes the rack 19 to rotate the pinions 21, which in turn transmit through the racks 22 an upward movement to the rod 24, which is thus transmitted to the forming block 25, the racks 18 at the same time acting upon the toothed sectors 28a to cause the weights 29 upon the outer ends of the levers 28 to be swung upwardly.

60 It is to be noted that in addition to ensuring an even and constant pressure between the two dies, the weight 29 also acts to return the moving parts 10 and 17 and also parts of the bottom die. In the event, however, of 65 the return of the parts being prevented, by

slackening, there are provided vertically disposed rods 39 secured at their upper ends by means of nuts 40 to lugs 41 formed integral with the ram 6 and arranged in pairs one upon each side thereof, the said rods 70 freely passing through the table 2 and through lugs 42 formed upon each side of the table 10, nuts 43 being provided upon the lower ends of the rods whereby when the ram moves upward these nuts engage the undersides of the lugs 42, and thus ensure that the table 10 is returned to its normal or uppermost position.

Claims:

1. In a press for sheet metal a movable die, a fixed die, a movable block in said fixed die, a pressure table, a fixed body, levers upon said body operatively associated with said pressure table, weights upon said levers, means operatively connecting the pressure table with said movable member of the fixed die in a manner such that the weights act to provide a constant resistance to the pressure of the tool and to return the parts after operation.

2. In a press for sheet metal, a movable die, a fixed die, a movable block in said fixed die, a pressure table, a fixed body, levers upon said body operatively associated with said pressure table, weights upon said levers, means operatively connecting the pressure table with said movable member of the fixed die in a manner such that the weights act to provide a constant resistance to the pressure of the tool and to return the parts after operation, and means for regulating the effect of said weights.

3. In a press for sheet metal, a movable die, a fixed die, a movable block in said fixed die, a rod connected to said block, a fixed body, toothed sectors mounted on said body levers associated with said sectors, weights upon said levers, a pressure table, members carried by the pressure table, racks on said members engaging the sectors, other means upon said members operatively engaging the rod of the movable member of the fixed die, said weights acting to provide a constant resistance to the pressure of the tool and to return the parts after operation, and means for regulating the effect of said weights.

4. In a press for sheet metal, a movable die, a fixed die, a movable block in said fixed die, a rod connected to said block, a fixed body, toothed sectors mounted on said body levers associated with said sectors, weights upon said levers, a pressure table, members carried by the pressure table, and engaging the sectors, pinions upon said body, other racks upon the members carried by the even pressure table engaging said pinions, racks upon the rod of the movable member of the fixed die engaged by said pinions.

5. In a press for sheet metal, a movable die, a fixed die, a movable block in said fixed die,

- a rod connected to said block, a fixed body, toothed sectors mounted on said body, levers associated with said sectors, weights adjustable upon said levers, a pressure table, members carried by the pressure table, and engaging the sectors, pinions upon said body, other racks upon the members carried by the even pressure table engaging said pinions, racks upon the rod of the movable member of the fixed die engaged by said pinions.
- 5 6. In a press for sheet metal, a movable die, a fixed die, a movable block in said fixed die, a rod connected to said block, a fixed body, toothed sectors mounted on said body, levers associated with said sectors, weights fixed to said levers, a pressure table, members carried by the pressure table, and engaging the sectors, pinions upon said body, other racks upon the members carried by the even pressure table engaging said pinions, racks upon the rod of the movable member of the fixed die engaged by said pinions, and brakes for regulating the effect of the weights.
- 10 20 25

In testimony whereof I affix my signature.

CHARLES JOSEPH RHODES.
